UNITED STATES PATENT OFFICE.

JAMES H. WILLIAMS, OF UTICA, NEW YORK.

METHOD OF MAKING HEDDLE-WIRES.

SPECIFICATION forming part of Letters Patent No. 366,056, dated July 5, 1887.

Application filed April 3, 1886. Serial No. 197,752. (No model.)

To all whom it may concern:

Be it known that I, JAMES H. WILLIAMS, a citizen of the United States, residing at Utica, in the county of Oneida and State of New York, have invented certain new and useful Improvements in the Method of Making Heddle-Wires; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention, and is a top view. Fig. 2 is an edge view.

The invention is an improved method of making stock for loom nails or heddles, and the accompanying drawings show the stock so formed, A designating the wire portion thereof, and B the bosses or swells, in which the eyes are bored after the stock is made.

The stock is produced by taking rods of annealed metal of proper diameter and drawing the same through dies that open at regular intervals of time. The dies by their action produce stems of equal diameter between the bosses, which are at equal distances apart,

and the bosses formed by the opening and closing of the dies have regular oval contours, the edges having similar forms on each side of their central transverse section-lines. When the stock is drawn, the eyes are punched or bored in the bosses and the stock cut up into lengths, the cuts being made centrally between the bosses. The bosses so made are wider but not thicker than the intermediate stem portions.

Having described this invention, what I claim, and desire to secure by Letters Patent, is—

The herein described method of making heddle-stocks for looms, which method consists in drawing an annealed metal rod between suitable dies that open and close at regular intervals of time to produce a flat boss having a regular oval contour, similar on each side of its transverse central line and forming, when closed, a stem portion between the bosses, of equal diameter throughout its entire length.

In testimony whereof I affix my signature in presence of two witnesses.

JAMES H. WILLIAMS.
